Patented Aug. 8, 1922.

UNITED STATES PATENT OFFICE.

GEORGE STRONG, OF LONDON, ENGLAND, ASSIGNOR, BY MESNE ASSIGNMENTS, TO JOSEPH DIXON CRUCIBLE COMPANY, OF JERSEY CITY, NEW JERSEY, A CORPORATION OF NEW JERSEY.

SHOWCASE.

1,425,347.

Specification of Letters Patent.

Patented Aug. 8, 1922.

Application filed July 19, 1921. Serial No. 485,863.

To all whom it may concern:

Be it known that I, GEORGE STRONG, a subject of the King of Great Britain and Ireland, and resident of London, England, 5 have invented new and useful Improvements in or Relating to Showcases, of which the following is a specification.

This invention relates to improvements in show or display cases and it has for its 10 object improvements by which certain advantages shall be obtained.

According to the present invention, a show or display case comprises the combination with a body, of a plurality of drawers 15 or trays mounted therein one above the other, and a lever of the first order fulcrumed on the side of the body to which the drawers or trays are operatively connected, one or more on one side of the fulcrum. The 20 drawers or trays or any of them may be connected to the lever by links.

A pair of similar levers mounted one at each side of the body and each operatively connected to the drawers or trays may be 25 provided and the said drawers or any of them may be mounted by hinges on a member carried on the pair of levers.

One form of the present invention will now be described with reference to the accompanying drawings, wherein:—

Fig. 1 shows a side elevation in section of the show case closed,

Fig. 2 a side elevation with the side wall removed of the display case opened, and

Fig. 3 a plan thereof.

The body comprises a base 1 and side walls 2 and has shelves or supports 3, 4, 5, which divide it into sections. The portion above the shelf 5 has a curved glass cover 6. 40 In the spaces between the shelves 3, 4 and 5 are drawers or trays 7, 8. A pair of levers 9, 10 are pivoted at 11, 12 to the side walls respectively and each lever is connected to the drawer 7 by a link 13 and to the drawer 45 8 by a link 14. The levers 9, 10 are connected by a cross member 15 which, when the case is closed, fills the opening 16 at the back. To the portion 15 is hinged at 17, 17 a tray 18 so that when the case is closed the 50 said tray is supported at an angle, as shown in Fig. 1. Under the shelf or support 3 is a

drawer 19 sliding in the space between the said support and the base 1.

The trays or drawers may be divided into sections by partitions 20.

The member 15 is provided with a handle or knob 21.

When it is desired to open the show or display case, the member 15 is pulled so that the levers 9, 10 rotate about their pivots 11, 12 60 whereby the tray or drawer 18 is withdrawn towards the rear and the trays or drawers 7, 8 are pushed out towards the front. The show or display case may be constructed of wood, cardboard or other material. 65

What I claim is:—

1. A display case comprising in combination a body, a pair of levers of the first order fulcrumed one on each side of the body, a drawer connected by links to each lever on 70 one side of the fulcrum, a cross member carried on the levers on the other side of the fulcrum, and a tray hinged to said cross member.

2. A display case comprising in combination a body, a pair of levers of the first order fulcrumed one on each side of the body, a shelf in the body, a drawer arranged under said shelf and connected by links to each lever on one side of the fulcrum, a cross 80 member carried on the levers on the other side of the fulcrum, a tray hinged to said cross member and bearing on the upper side of the shelf, and a transparent cover for the top portion of the case arranged over the 85 tray.

3. A display case comprising in combination a body, a pair of levers of the first order fulcrumed one on each side of the body, a plurality of drawers connected by links to 90 each lever on one side of the fulcrum, a plurality of shelves disposed one above each drawer, a cross member forming a closure for the case and carried on the levers on the other side of the fulcrum, a tray hinged to 95 said cross member and bearing on the upper side of the shelf above the top drawer, and a transparent cover for the top portion of the case arranged over the tray.

4. A display case comprising in combination, a body, a shelf mounted in said body and forming upper and lower compartments

therewithin, levers fulcrumed on each side of said body, a drawer mounted in said body beneath said shelf, links connecting said drawer with said levers below the fulcrum points thereof, a closure for the upper compartment of said body mounted on and carried by said levers above the fulcrum points

thereof, and a tray pivotally connected to said lever supported closure and bearing on said shelf within the upper compartment of 10 said body.

Dated this fourth day of July, 1921.

GEORGE STRONG.
